CLAIM

We claim the ornamental design for a cooking vessel, as shown and described.

DESCRIPTION

FIG. 1 is an isometric view, from the front top left, of a first embodiment of the cooking vessel.

FIG. 2 is an isometric view, from the back bottom right, of the first embodiment of the cooking vessel.

FIG. 3 is a plan view from the top of the first embodiment of the cooking vessel.

FIG. 4 is a plan view from the bottom of the first embodiment of the cooking vessel.

FIG. 5 is an elevation view from the front of the first embodiment of the cooking vessel.

FIG. 6 is an elevation view from the back of the first embodiment of the cooking vessel.

FIG. 7 is an elevation view from the right of the first embodiment of the cooking vessel.

FIG. 8 is an elevation view from the left of the first embodiment of the cooking vessel.

FIG. 9 is an isometric view, from the back bottom right, of the second embodiment of the cooking vessel.

FIG. 10 is an isometric view, from the front top left, of a second embodiment of the cooking vessel.

FIG. 11 is a plan view from the tops of the components of the second embodiment of the cooking vessel.

FIG. 12 is a plan view from the bottoms of the components of the second embodiment of the cooking vessel.

FIG. 13 is an elevation view from the front of the second embodiment of the cooking vessel.

FIG. 14 is an elevation view from the back of the second embodiment of the cooking vessel.

FIG. 15 is an elevation view from the right of the second embodiment of the cooking vessel;

FIG. 16 is an elevation view from the left of the second embodiment of the cooking vessel; and,

FIG. 17 is a cross-sectional view taken through line 17-17 of FIG. 3.

Any broken lines are understood to be for illustrative purposes only and form no part of the claimed design.
